Primary Examiner — Janice Seeger(74) Attorney, Agent, or Firm — Cislo & Thomas, LLP(57) CLAIM

I claim the ornamental design for a headboard, as shown and described.

DESCRIPTION

FIG. 1 is a perspective view of my headboard;

FIG. 2 is a front view thereof;

FIG. 3 is a top view thereof;

FIG. 4 is a right side view, the left side (not shown) is a mirror image thereof; and,

FIG. 5 is an enlarged view depicting the design of my headboard as shown in the called out encircled area 5 of FIG. 2. The broken lines are for environmental purposes only and form no part of the claimed design.
